UNITED STATES PATENT OFFICE

RICHARD M. FOX AND HARVEY E. SMITH, OF PORTLAND, OREGON, ASSIGNEES TO
AEROMETRIC VALVE CORPORATION, OF PORTLAND, OREGON

AIR-CLEANSING APPARATUS

Application filed March 14, 1929. Serial No. 346,862.

This invention relates generally to the use of compressed air, and particularly to devices for removing from the air dust and other forms of foreign matter having a higher specific gravity than does the air itself.

The main object of this invention is to produce an exceedingly simple and efficient valve for removing foreign substances from a compressed air line before the air is delivered to a pneumatic tire, tool, or other contrivance in which the presence of dust, moisture, or other solid or liquid would interfere with the proper functioning of the valves or working parts of the particular device to which air is being delivered.

The second object is to so construct the valve as to utilize the well known inertia of movement, as well as the inertia of rest, to separate heavier than air foreign substances from the air and to maintain this separation until an accumulation of such foreign matter is removed from the valve.

The third object is to so construct the valve as to utilize not only the changes of direction for the purpose of separating the heavier materials from the air, but also changes in volume and velocity, in addition to gravity itself.

The fourth object is to so construct the valve that any abnormal out flow of air through the valve will be prevented by an automatic increase in the back pressure or restriction offered to the flow of air.

The fifth object is to provide an inexpensive device for the thorough cleansing of compressed air before it is delivered to pneumatic tires or air operated devices of any kind, or where air is used for cleansing purposes, as in dental or horological work.

The sixth object is to produce a cleansing valve which will make it possible to dispense with cumbersome and expensive washing apparatus such as is commonly employed.

These, and other objects, will become more apparent from the specification following as illustrated in the accompanying drawing, in which:

Figure 1 is a vertical section through the device showing the normal passage of air therethrough. Figure 2 is a view similar to

Figure 1 but showing the position of the parts when resisting the flow of abnormal quantities of air. Figure 3 is a section taken along the line 3—3 in Figure 2. Figure 4 is a horizontal section taken along the line 4—4 in Figure 1.

Similar numbers of reference refer to similar parts throughout the several views.

Referring in detail to the drawing, the device in its preferred form consists of a body 10 whose lower end 11 is threaded upon an air supply pipe 12, to which air is delivered from any convenient source (not shown). In the body 10 is also provided a drain plug 13 whose point 14 normally closes the drain opening 15. A side outlet 16 is provided for the exit of foreign matter when the plug 13 is opened. On one side of the body 10 is formed a boss 17 into which is threaded a delivery pipe 18 for cleansed air through which air may pass to a tire-inflating valve, or other mechanism, as above suggested.

Threaded into the top side of the body 10 is the threaded shank 19 of the tube nut 20 which is formed at the base of the intake tube 21, which should stand in a vertical position. Inside of the intake tube 21, and secured at the lower end thereof to the nut 20, is an outlet tube 22 whose upper end extends well above the top of the intake tube 21.

In the body 10 is formed an inlet passage 23 which communicates between the pipe 12 and the top side of the nut 20 between the tube 21 and the tube 22. Around the outside of the tube 21 is placed a spreader 24 whose top side slopes downwardly toward its outer edge, which is circular in form.

Slidably mounted on the portion of the tube 22 above the tube 21 is a metering thimble 25 which is somewhat conical in shape having its smaller end uppermost and having a shoulder 26 formed at the lower end thereof. Integral with the metering thimble is a metering mantle 27 which extends downwardly around the outside of the intake tube 21 and spaced therefrom and almost reaching the top of the spreader 24, when the lowermost side 38 of the thimble 25 rests upon the shoulder 39 formed on the tube 22.

In the body 10 is also provided an outlet

passage 28 which communicates between the pipe 18 and the recess 29 into which the shank 19 is threaded. Around the outside of the body 10 is formed an internally threaded flange 30 into which is threaded a cylindrical casing 31 whose upper end 32 is closed and on its top side is provided a nut 33 by means of which the casing 31 may be rotated. On the under side of the member 32 is formed an outlet tube housing 34 having a cylindrical recess 35 formed therein and outer walls 36 which taper downwardly to the edge 37 adapted to engage the shoulder 26 when the metering mantle 27 is sufficiently raised by an abnormal flow of air through the valve.

The shank 19 is provided with a channel 40 which communicates between the pipe 18 and the outlet tube 22.

In order to better explain the operation of this device the various zones where changes occur will be referred to as follows: Zone 1 indicates the location of the first turn in the incoming air, namely as the air leaves the intake tube 21 and enters the metering mantle 27. Zone 2 indicates the second change in direction and lies between the bottom of the metering mantle 27 and the top of the spreader 24. The third zone indicates the location of the third change in direction, namely at the extreme top of the casing 31. Zone 4 indicates the fourth change in direction between the metering thimble 25 and the outlet tube housing 34. Zone 5 represents the fifth change in direction, which is at the top of the inside of the outlet tube 22 and is the last change of direction contributing to the separation of the foreign matter from the air.

The operation of the device is as follows: Let us assume that it is mounted in the position shown in Figure 1 of the drawing, namely on an air supply pipe 12 and having its delivery tube 18 connected to an air delivery line (not shown) by means of a coupling 41 which may be operated by means of a handle 42. If it is desired to deliver cleansed air from the pipe 12 through the pipe 18 for any purpose whatsoever, air is permitted to escape from the device by means of a valve (not shown) usually in the immediate vicinity of the tire inflating chuck or air tool. Air now enters the device from the pipe 12 passing through the inlet passage 23 and the outlet tube 22 escaping into zone 1 where its direction of travel is reversed sending it downwardly against the top of the spreader 24, or into zone 2.

In zone 1 the air receives its first reduction in velocity, its first increase in volume and first change in direction and is now projected against the top of the spreader 24, as stated, causing the heavier than air particles to roll downwardly and fall between the spreader 24 and the casing 31 into a trap 6, from which any accumulation can be removed by opening

the drain plug 13 which will permit the accumulation to be blown out.

While the major portion of the heavier than air particles are removed in zone 2, as stated, a small quantity may be found traveling upwardly from the second zone to a point about half way up the casing 31 where there is formed an eddy current zone 7, the major portion of the air traveling upwardly to zone 3 where the third reversal in direction of travel occurs, this time not effecting its velocity or volume, after which the air passes downwardly along the outlet tube housing 34, which directs the current of air toward the center of the casing 31. The outlet tube housing 34 is of such length and shape as to bring about a rapid reverse in the air flow in zone 4, which increases the velocity and decreases the volume.

As the air travels downwardly from zone 3 to zone 4 the outermost portion of the current contacts with the expanded portion of the air in zone 7, causing an eddy current to take place therein which, in turn, causes the heavier than air particles that may have traveled to this point to be thrown outwardly where they descend along the outer surface of the metering mantle 27 into the trap 6.

After the air has passed from the fourth zone into the top of the outlet tube 22, which constitutes the fifth zone, it is reversed in direction for the fifth time and enters the outlet tube 22, where it regains its original velocity and volume.

It will be seen that as the flow of air increases through the delivery pipe 18 the metering mantle 27, with its metering thimble 25, slides upwardly along the outlet tube 22 causing an increased restriction to the flow of air from zone 4 to zone 5, thereby automatically throttling the flow of air which prevents the air from leaving the device too rapidly or in an unclean condition.

It will be noted that the upward travel of the metering mantle 27 is limited by the shoulder 26 coming in contact with the lower edge 37 of the outer wall 36 and the lowermost position of the mantle 27 is determined by the shoulder 39 on the outlet tube 22.

As soon as the outgoing and incoming volumes become sufficiently equalized the restriction will be removed by a downward sliding of the metering mantle 27. It is clear that the point of equalization will depend largely upon the volume consumed, as well as weight of the moving parts, and the relative areas of the various passages through which the air must travel.

For the purpose of illustrating the path of the air currents same will be shown as full line arrows 43, whereas the heavier than air particles will be shown as short dotted lines 44, and the precipitated particles 45 will be shown as small dots.

It will be noted that the lower edge 46 of

the metering mantle 27 is bell shaped and curved to prevent the formation of eddy currents between the metering mantle 27 and the spreader 24, which formation would retard the escape of the foreign matter into the trap 5 6.

While this device has been described as being placed in delivery lines, it could of course be placed on the suction side of a 10 compressor for the purpose of keeping foreign matter out of the compressor parts; in fact, it can be used any place where air is in motion, although obviously the benefits are most apparent where the air is carried at 15 several atmospheres of pressure.

While we have thus illustrated and described our invention, it is clear that numerous changes can be made in the details thereof without departing from the spirit of the invention, such as the curvature and size of the 20 reversing bends, as well as in the number of reversals and changes in area employed, and in the form and position of attachments to any apparatus using air. No limits of use 25 by reason of form is contemplated as confined to any particular structure or position.

We are aware that various devices have been constructed in the past for filtering air; we therefore do not intend to cover such 30 devices broadly, but we do intend to cover all such forms and modifications thereof as fall fairly within the appended claims.

We claim:

1. An air cleanser consisting of a body having 35 inlet and outlet ports formed therein, a scavenging valve mounted therein, an upright intake tube mounted on said body communicating with said inlet port, an outlet tube within said inlet tube communicating 40 with said outlet port, a spreader surrounding the base of said inlet tube forming a trap on the under side of same, a metering mantle slidably mounted on the upper end of said outlet tube, a casing on said body enclosing 45 said spreader and mantle, an outlet tube housing surrounding the upper end of said outlet tube forming a top for said casing, the lower end of said housing constituting an outlet opening for the cleansed air, and the mantle 50 constituting a closure for said outlet opening whereby the flow of air through said device is governed.

2. In an air cleansing device the combination of a bell-shaped metering mantle, an 55 outlet tube on which said metering mantle is slidably mounted, an outlet tube housing having a recess into which said outlet tube projects having a space between said housing and tube through which air must pass before 60 entering said outlet tube, said mantle having a thimble formed thereon adapted to restrict the opening between said outlet tube and housing, and an inlet tube adapted to project air into said bell-shaped mantle in a manner 65 to slide same toward said housing when the

flow of air exceeds a predetermined maximum.

3. An air cleansing apparatus consisting of a chamber having a tortuous passageway formed therein through which air can pass 70 in opposite directions, said passageway having varying areas adapted to provide varying velocities for the air traveling therethrough, the bends in said passageway forming points of reversal at which heavier than 75 air particles are extracted by inertia, a trap forming an auxiliary to said passageway having a dead air space therein for the collection of heavier than air particles, and a metering mantle restricting the area of the passageway 80 when the flow of air through the apparatus exceeds a predetermined maximum.

4. An air cleansing apparatus having a tortuous passageway comprising sections through which air can flow in successively 85 reversing directions and passing through successive changes in velocity and volume whereby heavier than air particles contained therein will be separated from the air at the point of reversal and change of velocity, a trap 90 compartment formed within said device communicating with said sections for the admission of solids, and means for limiting the flow of air through said tortuous passage for the purpose of preventing the agitation of 95 trapped solids as well as the separation of solids from the air passing through the device.
